UNITED STATES PATENT OFFICE.

SYDNEY GEORGE FROST, OF TWICKENHAM, ENGLAND.

SIGNALING UNIT FOR WIRELESS TELEGRAPHY.

1,424,294.

Specification of Letters Patent. Patented Aug. 1, 1922.

Application filed May 11, 1922. Serial No. 560,007.

To all whom it may concern:

Be it known that I, SYDNEY GEORGE FROST, of Twickenham, in the county of Middlesex, England, a subject of the King of Great Britain and Ireland, have invented certain new and useful Improvements in Signaling Units for Wireless Telegraphy (for which I have filed application in England, November 15, 1920, No. 175,720), of which the following is a specification.

This invention relates to an emergency high tension generator for wireless signaling purposes and particularly suitable for use on aircraft or the like.

15 The invention comprises the combination, in a magneto electric generator, of an armature rotatable from a driving shaft through magnifying gearing and adapted to provide direct current potential for operating 20 a high or low tension wireless transmitter in conjunction with a detachable or changeable rotatable signal switch for automatic transmission of Morse signals of audible frequency. The signal switch is driven from 25 the driving shaft direct or through reduction gearing, and the whole forms a single unit.

The invention is illustrated in the accompanying drawings, in which—

30 Fig. 1 is a side elevation of one form of construction;

Fig. 2 is an end elevation, parts being omitted;

Fig. 3 is a plan, parts being omitted;

35 Figs. 4 and 5 are an elevation and an end view of a serrated switch;

Fig. 6 is a sectional elevation of a modification;

40 Fig. 7 is a sectional elevation of another modification;

Figs. 8 and 9 are end elevations; and

Fig. 10 is a circuit diagram.

Like reference letters indicate like parts where repeated in the drawings.

45 As shown, the generator comprises a permanent magnet or magnets 7, an armature 8, the spindle of which is rotated through speed gearing, 9, and a handle 10, on a driving spindle 11. In Fig. 1 the driving 50 spindle and the armature spindle are mounted in antifriction bearings 12, and in Fig. 7, the driving spindle turns in plain bearings, in brackets 13.

14 is a multi-section commutator on the 55 armature spindle in series with the armature winding, and 15, 16 are brushes.

17 is a serrated rotary switch which, in Fig. 1 is mounted on the driving spindle 11, and in Fig. 7 is mounted on a countershaft 29, extending from a boss plate 30, connected 60 by screws 31, to a gear wheel 32, driven at reduced speed by a pinion 33, on the driving spindle. The switch 17, has a plain conducting portion 18. 19, 20 are brushes.

It will be seen that the serrated switch 17 65 is fitted with conductive segments 21, for transmitting an emergency call signal, and is housed within the permanent magnet, Fig. 1, or between the magnets and beneath the condenser 34, Fig. 8. The signal switch 70 17, may be readily removed and replaced by removing the nut 22, (Fig. 1). Or, as shown in Figs. 6 and 7, the signal switch may be constructed to push it on to a square portion 75 23, of the driving spindle 11, or the countershaft 29, so as to be removed and replaced by simply pushing or pulling a knob 24, on the signal switch. In Figs. 6 and 7, the brushes 19, 20, consist of balls pressed by springs 25, 26, into engagement with a conducting peripheral groove 28, and an interrupted conducting peripheral groove 27, around the signal commutator.

The apparatus may be arranged, as shown in Fig. 10 with one brush 15, of the armature commutator 14, connected to one brush 20, of the signal switch 17, and with the other brushes 16, 19, connected to the respective terminals of the external circuit. The 85 signaling apparatus is then ready to be operated by an unskilled person.

90 One of the brushes 15, of the armature commutator may be connected to the external circuit through a two-way switch 49, and the terminals of the signal switch may be 95 short-circuited or put out of circuit thereby, so that the signaling apparatus may be used by a skilled person by operating a key 47, to transmit any desired signal. When the switch 49 is not connected to the brush 15, 100 and is on stud 50, the generator automatically transmits a predetermined emergency signal, or a succession of such signals, by wave telegraphy by rotating the driving spindle 11 by means of the handle 10, thus 105 also rotating the armature 8 and signal switch 17. When the switch 49, is connected to the brush 15, and is on stud 51, the signal switch is short circuited and signals may be sent by a skilled operator operating a 110 Morse key 47, in the external circuit. When the signal switch is short circuited or re-

moved the generator may be used for supplying direct current to a wireless receiver.

What I claim and desire to secure by Letters Patent is:—

- 5 1. A signaling unit for wireless telegraphy or the like comprising in combination an electric generator, a rotor therein, means for rotating the rotor, connections for associating the rotor in a transmitting circuit, and
- 10 10 means mechanically controlled by said first means and operating in conjunction with the rotor in said connections for transmitting telegraphic signals.
- 15 2. A portable signaling set for wireless telegraphy comprising in combination a magneto-electric generator, a rotor therein, a rotatable signaling device, means thereon for transmitting a predetermined signal by the rotation of the device, electric connections from the rotor to the signaling device and from the rotor and the signaling device to a transmitting circuit, a driving shaft, and means mechanically connecting the driving shaft both with the rotor and also with
- 20 25 the rotatable signaling device.
- 25 3. In a signaling unit for wireless telegraphy, the combination with an electric generator, of a rotatable armature therein, means for rotating the armature, a wireless transmitter, electric connections from the armature to the transmitter, a rotary switch in said connections, means for causing the switch to be rotated in conjunction with the

rotation of the armature, and means on the switch for giving Morse signals when the 35 armature is rotated.

1. In a signaling unit for wireless telegraphy, the combination with a magneto-electric generator, of a rotatable armature therein, means for rotating the armature, a 40 transmitting circuit connected to the armature, a rotary switch and a Morse key connected to said circuit, means for causing the rotation of the armature to rotate the rotary switch, means on the rotary switch for 45 transmitting a predetermined signal by the rotation of the switch, and means enabling either the rotary switch to transmit the predetermined signal, or the said rotary switch to be cut out and the Morse key to be used 50 instead to transmit any desired signal.

5. In a signaling unit for wireless telegraphy, the combination with a magneto electric generator, of a rotatable armature therein, a rotary switch in circuit with the armature, a second transmitting circuit connected to the armature, a telegraphic key in the said second circuit, means for optionally employing either the rotary switch or the telegraphic key to produce wave signals, 60 and means for rotating the armature and switch.

In testimony whereof I have signed my name to this specification.

SYDNEY GEORGE FROST.
